UNITED STATES PATENT OFFICE.

WILLIAM J. LANE AND GEORGE LANE, OF POUGHKEEPSIE, NEW YORK.

WATER-LEVEL REGULATOR.

No. 809,510.

Specification of Letters Patent.

Patented Jan. 9, 1906.

Application filed February 15, 1905. Serial No. 245,701.

To all whom it may concern:

Be it known that we, WILLIAM J. LANE and GEORGE LANE, citizens of the United States, residing at Poughkeepsie, county of Dutchess, 5 State of New York, have invented certain new and useful Improvements in Automatic Water-Level Regulators, of which the following is a specification.

This invention relates to a device adapted 10 to be used in connection with a steam-boiler, and which has for its purpose to automatically regulate the level of the water in a boiler.

The device in its simplest form consists of a body—for instance, a metal bar—which will 15 expand and contract under variations of temperature and a device—for instance, a valve—adapted to be moved by said body and which will in some manner control the water-supply of the boiler.

20 In the present case a valve is employed to control a by-pass from the source of water-supply, which is normally open, but which is closed when the water-level of the boiler falls below a predetermined point.

25 The accompanying drawings will serve to illustrate my invention.

Figure 1 is a side elevation and partial vertical section taken through a motor-vehicle, showing the regulator in the position which 30 it would occupy relative to the boiler and the water-circulation. Fig. 2 is a side view of the regulator and longitudinal section through the by-pass valve. Fig. 3 is a plan view.

Referring to the drawings, 5 indicates a 35 pipe connected at its lower end and to the interior of a boiler 6 at a determined maximum water-level. Connected to the upper end of this pipe is a second pipe 7. The pipe 7 is mounted in a frame 8 by means of a bolt 40 10. The other end is loose and situated in an opening 11 in a projection 12 from frame 8. Pivotaly mounted in frame 8 at 13 is a lever 14. The lower end of this lever has an opening 15, in which is located the stem 16 of 45 a by-pass valve 17. Situated on the stem 16 is an adjustable stop 18. The stem 16 to the left of the lever 15 is enlarged and is situated in an opening 19 in the projection 12 of the frame 8. On the end of this portion of 50 stem 16 is a collar 20, and situated between the collar and the projection 12 is a helical spring 21.

Mounted upon the lever 15 is a thread-adjusting pin and set-screw 22. 55 23 represents a pipe from the source of water-supply 24, and 25 a constantly-operated

pump; 26, a pipe from the outlet of pump to by-pass valve 17 and communicating through branch pipe 27 with the interior of the boiler; 28, a pipe from by-pass valve to pipe 23, and 60 29 a check-valve in pipe 27.

The action of my device may be described as follows: Pump 25 draws the feed-water from tank 24 through pipe 23 and delivers it through pipe 26 to a by-pass valve 17, and as 65 assuming the water-level of the boiler to be at the maximum the water passes through the by-pass valve and flows by pipe 28 back to the pump. Should the water-level of the boiler fall below the maximum, steam will enter the pipe 5. The temperature of this steam will expand pipe 7, which in turn will move lever 15 and a valve-stem 16, thereby closing the by-pass valve. Water from pump 25 at such time will flow down pipe 26 75 and through branch pipe 27 into the boiler to restore the normal water-level. The entrance of water into pipe 5, thereby cutting off the steam from the boiler, will cause a contraction of the pipe 7, and the by-pass valve 17 80 will be opened by the spring 21.

Having thus described our invention, we claim—

1. An automatic water-level regulator for 85 a steam-boiler comprising a pipe connected at one end to the normal water-level of the boiler, a pipe connected to said first-named pipe, a frame in which said second-named pipe is located and in which it is secured at one end, a lever pivoted in the frame, an adjustable connection between said lever and said second-named pipe, and a valve in the water-supply 90 connections to be actuated by the movement of said lever.

2. An automatic water-level regulator for 95 a steam-boiler comprising a pipe connected at one end to the normal water-level of the boiler, an expansible body connected to said pipe, a lever mounted independent of said expansible body and in operative relation thereto, means for adjusting the lever relatively to said expansible body, a spring-opened valve adapted to be closed by the movement of the lever, and adjustable means 100 for regulating the movement of the valve. 105

In testimony whereof we affix our signatures in the presence of two witnesses.

WILLIAM J. LANE.
GEORGE LANE.
